UNITED STATES PATENT OFFICE.

ROBERT E. COLOMY, OF CUMBERLAND, MARYLAND.

COMPOSITING SIGN.

Application filed October 19, 1921. Serial No. 508,692.

To all whom it may concern:

Be it known that I, ROBERT E. COLOMY, a citizen of the United States, residing at Cumberland, in the county of Allegany and State of Maryland, have invented certain new and useful Improvements in a Compositing Sign, of which the following is a specification.

The present invention relates to a compositing sign for the purpose of displaying on a single line successive groups of words or phrases thereby presenting a complete paragraph or thought or several separate units of composition as may be desired.

Another important object of the invention is to provide a sign of this nature which will be of extremely simple, durable and inexpensive construction, one which is efficient and reliable in operation, and well adapted to the purpose for which it is designed.

With these and numerous other objects in view, the invention resides in certain novel features of construction, and the combination and arrangement of parts as will be hereinafter more fully described and claimed.

In the drawing:—

Figure 1 is a rear elevation of the sign.

Figure 2 is a plan view of the sign board.

Figure 3 is a transverse section taken on the line 3—3 of Figure 2.

Figure 4 is a transverse section taken on the line 4—4 of Figure 3 looking in the direction of the arrow,

Figure 5 is an enlarged detailed sectional view of the displaying leg of the raceway,

Figure 6 is a similar view of the bottom leg of the raceway,

Figure 7 is a transverse section taken on the line 7—7 of Figure 6,

Figure 8 is a detailed plan view of the spool and its spring used in connection with the device, and

Figures 9 and 10 are detailed views showing slightly modified forms of the index panels and their rollers with corresponding constructions of the raceway.

Referring to the drawing in detail it will be seen that the frame 1 is provided with a plurality of upright standards 2 and a raceway 3 is arranged thereon. This raceway consists of the horizontally disposed displaying leg 4 and the bottom leg 5 which are connected at one end by the vertically disposed leg 6 and at their other ends by the zigzag arrangement which consists of

a plurality of transversely disposed inclined legs 7 connected by the curved portions 8. An inclined portion 9 communicates the display leg 4 with the vertical leg 6 so that each index panel and its cooperating parts to be hereinafter explained, may individually or separately enter the display leg 4.

Any suitable casing may be provided for the mechanism thus far described which consists of at least a sign board 10 having a display opening 11 therein. This display opening 11 is in registry with the display leg 4 so that the index panel situated therein may be seen therethrough.

By referring especially to Figures 3, 4 and 7 the preferred or common construction of the index panels and their cooperating mechanism will be seen. The panels 12 are preferably disposed in a vertical plane although this may be varied as is shown in the modified construction illustrated in Figures 9 and 10. A weight element 13 is disposed at the lower edge of the panel 12 for the purpose of retaining the same in an upright position. The panels 12 are provided with suitable indices such as letters or numerals and of course will be arranged so as to form words or phrases which may be read through the displaying opening 12 as is indicated in Figure 2. Some of the panels will be blank so as to represent spaces as in ordinary type.

A ball bearing sleeve 14 is centrally located on the rear face of each index panel 12 for the purpose of receiving ball bearings so that the panels will be rotatably mounted on the axles 15 of the rollers 16 which are mounted in the raceway. This roller 16 may be of varying construction such as, for example, as shown in Figures 9 and 10 and of course the raceway will be correspondingly conformed thereto.

A guide frame 18 is situated beneath and fixed to the bottom leg 5 and has slidably mounted therein a block 19 provided with a suitable operating handle. A spring pressed finger is mounted in the block so as to engage the rollers as is clearly seen in Figure 6. When the block 19 is moved to the right as illustrated in the drawing, the panels to the right thereof will be moved into the vertical leg 6 and retained therein by the spring pressed finger 20. A cable 21 is attached at one end to the block 19 and passes over pulleys 22 and is wound about a drum 23.

Therefore, as the block 19 is moved to the right this cable 21 will be pulled so as to unwind from the drum 23 and in doing so, will cause the spring 24 to wind up with it attached thereto so that when the block 19 is released this spring 24 will return the same to its original or extreme left position as seen in Figure 1. The spring pressed finger of the block 19 is beveled on its left side so that in moving to the left it will be depressed in these blocks and not force the roller to its left to be moved thereby. A block 26 is attached to the cable 21 adjacent the drum 23 and is provided with a leaf spring finger 27 which is slanted upwardly to the left as disclosed in the drawing, whereby it will only engage the rollers so as to move them when moving from right to left as seen in the drawing. Thus, as the block 19 is moved to the right, the extreme right-hand end of the guide 18 the index panels will be moved from the bottom leg 5 into the vertical leg 6 and those panels mounted in the vertical leg 6 will be moved to the horizontally disposed display leg 5 and as they move down the slight incline 9 they will separate from each other for a sufficient time to allow the panels to right themselves. When the block 19 is situated to the extreme right-hand end of the guide 18 the block 26 is situated to the extreme right-hand end of the leg 4 and will move therefrom as it returns all those panels which made up the old phrase which is being moved from out of registry with the display opening 11.

Any suitable type setting mechanism may be used that is capable of conveniently arranging the index panels and in order to facilitate the entrance of the panels into the raceway 3, I have provided the hinged curved portion 30 which is situated so as to connect the display leg 4 with the uppermost slanting leg 7. Thus when this portion 30 is hinged downwardly the panels and their

rollers may be entered into the uppermost slanting leg 7.

While the preferred embodiment of my invention has been described in detail, it will be understood that I do not wish to be limited to the particular construction set forth, since various changes in the form, material, proportions, and arrangements of parts and in the details of construction may be resorted to without departing from the spirit and scope of the invention, or destroying any of the advantages contained in the same, heretofore described and hereinafter claimed.

Having thus described my invention what I claim as new is:

1. A sign of the class described comprising in combination a continuous raceway including a hinged portion so that entrance may be had thereto, and a plurality of panels movably mounted in the raceway.
2. A sign of the character described comprising in combination, a continuous raceway and a plurality of index panels movable therein, each consisting of a panel portion and a roller, a weight fixed to the panel portion so as to retain the same in an upright position.
3. A sign of the class described including in combination a continuous raceway composed of a display horizontally disposed leg, a zigzag portion situated therebelow and connected thereto at one end, a vertical leg connecting the lower end of the zigzag portion with the display leg and an incline portion disposed between the vertical leg and the display leg, and a plurality of index panels movable in the raceway.

In testimony whereof I affix my signature in presence of two witnesses.

ROBERT E. COLOMY.
